Primary Examiner — Cynthia Underwood(74) Attorney, Agent, or Firm — Cook Alex Ltd.CLAIM

The ornamental design for decorative glass, as shown and described.

DESCRIPTION

FIG. 1 is an isometric view of the new decorative glass design showing the entire decorative band in phantom;
 FIG. 2 is a front elevational view of FIG. 1;
 FIG. 3 is a top plan view of FIG. 1; and,
 FIG. 4 is a bottom plan view of FIG. 1.
 The broken lines represent portions of the structure that forms no part of the claim.
